CHARLES GUERITEY, OF PASSAIC, NEW JERSEY, ASSIGNOR TO E. W. BLISS COMPANY, OF BROOKLYN, NEW YORK, A CORPORATION OF DELAWARE.

CAN-HEADING MACHINE.

Application filed December 31, 1926. Serial No. 158,283.

The present invention relates to a machine adapted for heading non-circular cans or can bodies of the type wherein the seaming rolls revolve around the stationary mandrel holding the can end and are conformed in a manner complementary to the shape of the can, so that as they roll around it they turn and set the seam. The machine is applicable for bottoming can bodies or for topping 10 filled cans.

The object of the invention is to improve upon the machines of this type, to render the revolving head more compact, to enable the speed of rotation, and therefore the output of the machine, to be increased, to provide for better lubrication than heretofore, and in other ways to perfect the operation of the can head seaming elements.

The preferred embodiment of the invention is illustrated in the accompanying drawings, wherein,

Figure 1 is a side elevation, partly in vertical section, in planes indicated by the lines 1^a and 1^b in Figs. 2 and 3.

Fig. 2 is a plan view partly broken away and in section in planes indicated by the line 2-2 in Fig. 1.

Fig. 3 is a horizontal section in the planes indicated by the line 3-3 in Fig. 1.

Fig. 4 is a vertical section in a plane at right angles to Fig. 1, and indicated by the line 4-4 of Figs. 1 and 2.

Fig. 5 is a horizontal section in the plane of the line 5-5 in Figs. 1 and 6.

Fig. 6 is a fragmentary vertical section in the plane of the line 6-6 in Fig. 5.

Fig. 7 is a plan of one of the gears shown in Figs. 5 and 6, and

Fig. 8 is a perspective view of a coupling element.

Fig. 9 is a sectional elevation looking in the same direction as Fig. 4, the plane of the sectional portion being indicated by the line 9-9 in Fig. 2.

Fig. 10 is an elevation looking in the same direction as Fig. 9, partly broken away in the same sectional plane as Fig. 9 and illustrating a modified construction.

Fig. 11 is a horizontal section of the head alone, all other parts being removed, the plan of the section being on the line 11-11 in Fig. 9.

Fig. 12 is a plan of one of the slides shown as withdrawn from its slideway in Fig. 11.

Fig. 13 is an elevation of such slide looking from the bottom in Fig. 12.

Fig. 14 is a side elevation, on a reduced scale, of the upper part of Fig. 1, showing a modified construction.

Fig. 15 is a plan of a locking plate detached.

The machine in general is of a well-known type of machine having a suitable fixed frame which includes a bracket arm or horizontal extension A at the top, this being the only portion of the machine frame which is shown in the drawings. This arm forms the bearing support for drive shaft B, by which the working elements are rotated. In the fixed arm A is fastened a stationary shaft or spindle C which carries at its bottom end a stationary mandrel D, forming as usual the upper member of the can-holding chuck. Around the fixed spindle C is mounted the hub portion of a revolving head E. To the top of this head is fastened a bevel gear F which meshes with a bevel pinion F' on the drive shaft B wherefrom the head E is driven.

The head E, which is shown as a single casting, comprises an upper flange E', a middle tubular hub portion e, and a lower plate or disk f, the latter being formed as a preferably flat plate having openings f' f' on opposite sides, as shown in Fig. 11. In these openings move slides G G, one of which is shown separately in Figs. 12 and 13. Each of these slides has a vertical opening g with parallel sides serving to receive a carrier H which is clamped fast to the slide G; the carriers H H carry the spindles I I of the seaming rolls or seamers J J'. These seamers are conformed as shown in Fig. 5, so that their exterior contours are complements to the form of the mandrel D; that is, where the mandrel is an unequal sided quadrilateral with rounded corners (as shown in dotted lines in Fig. 5), the seamers are so shaped that as they rotate in engagement with the mandrel they bear equally against it at all portions of its perimeter, being formed with hollows entered by the salient portions of the mandrel, and with projecting curved portions engaging the flat sides of the mandrel. In the construction shown, this conformation is that peculiar to a gearing in the ratio of 2 to 3, so that for the two long flat sides of the mandrel there are provided on each

100
105

seamer three major projections, and between these are minor projections corresponding to the shorter flat ends of the mandrel, and between the major and minor projections 5 are hollows or concavities conforming to the four rounded corners of the mandrel.

In a machine of this type it is necessary that the seamers be revolved on their axes in a given gearing ratio to the mandrel (in 10 this case 3 to 2); that they be movable toward and from the mandrel, so that first one and then the other may act upon the can head to seam it down, and that they be so geared that when retracted out of action 15 they will continue to revolve in perfect step so as to properly mesh when brought into action; and that their respective movements be so timed that the first seamer will be first advanced into working engagement with 20 the can head, and after performing its part of the work of seaming, shall be retracted, and then the second seamer be advanced and held in engagement until its work is performed, and then retracted. The means for 25 performing these functions will now be described.

Rotating the seamers.—Heretofore such seamers have been mounted on the lower ends of upright shafts hung pendulously at their 30 upper ends and there provided with planet gears revolving around a sun gear on the stationary central spindle; and provided with means for swinging their lower ends radially to bring one seamer or the other 35 into or out of action. According to the present construction the seamer spindles I I are mounted vertically to have a parallel movement (instead of a swinging movement), for which purpose they have bearings 40 in the slides G, which slides have straight line radial movements in a horizontal plane. This has the advantage that the seamers have a parallel horizontal, instead of a swinging, movement. This facilitates 45 the slowing down of the seamers to a lower gear ratio than heretofore, which because it necessitates making them of larger radius, would occasion inconvenience if they had a swinging movement. To provide for 50 this new mounting and movement the present invention introduces a different form of gearing for driving the seamers.

A stationary or sun gear K is carried by the stationary spindle C at its lower end and 55 preferably just above the mandrel D. In continuous mesh with this are two planet gears L L, and directly below these are two seamer gears M M'. As the rotation of the head E carries the seamer spindles I around, the gears L L roll around in mesh with the sun gear K and consequently are rotated in the determined ratio; their rotation is communicated through a coupling device to the gears M M' respectively, so that the latter 60 revolve in perfect timing with the gears L L

(each having the same number of teeth). Thus, when the gears M or M' are by the movement of the slides H carried away from the mandrel, so that they are brought out of mesh with the gear K, they are nevertheless 70 kept in rotation at the same speed through the intermediation of the coupling. The gears L L are kept in mesh with the gear K by having a hub portion 12 which revolves within an annular bearing 13 formed in a 75 plate l (called an outboard bearing) which is fastened beneath the disk f (see Fig. 9). The gear L has an opening 14 (Fig. 7) amply large to provide for the radial movement of the spindle I which passes through 80 it. The gears L and M or M' are coupled together by a coupling N shown in Fig. 8, consisting of a ring having lower arms 15 which enter notches 16 (Fig. 7) in the gear L, and upper arms 17 which engage notches 85 18 in a flange 19 formed on the spindle I (Figs. 5, 6 and 9). The respective arms are arranged at right angles to each other and diametrically of the ring, and have parallel sides, so that they may slide in the respective notches 16 and 18; consequently they 90 can adapt themselves to the eccentricity due to the movements of the spindles toward and from the center of rotation. Thus rotation is communicated from the gears L to the 95 spindles I, and as the gears M M' are keyed on the lower ends of these spindles, these latter gears are driven in exact timing with the gears L L. The seamers J J' are fastened in non-rotative manner to the gears M M' 100 (or otherwise to the spindles) as by bolts 20.

The spindles I I are provided with suitably prolonged bearing bushings h within the carriers H, and are desirably made hollow in order to receive grease or other lubricant. Oil holes 21 (Fig. 6) are provided for admitting the lubricant to the coupling N. 105

The spindle carriers H are essentially a part of the slides G, since they are clamped fast to the slides and move with them. They are, however, adjustable radially with reference to the slides, so that the spindles I I may be set to different distances from the central axis of rotation. The purpose of 110 this is to provide for the initial adjustment of the machine and its readjustment incident to the changing of the seamers J J' and mandrel D to adapt the machine for different sizes or shapes of cans. To enable 115 the carriers H to be clamped fast to the slides G, they are made in two parts; the bushing h is housed in a tubular standard i projecting from a square or flat-sided body j beneath; this portion j has a shoulder 22 120 which fits beneath a shoulder 23 (Fig. 13) in the slide G so as to resist upward movement; above the body portion j is a cap portion k having a recess which engages over 125 the tubular portion i, and its bottom resting 130

on top of the slide G, as shown at the left in Fig. 6; thus the slide G may be clamped between the cap portion k and the shoulder 22; to perform this clamping, a ring or nut 23 is screwed down upon a threaded upper portion of the tubular member i. By setting back the nut 23 the parts are so released that the carrier H may be slid radially within the opening g in the slide G, and by proper adjustment may be set fast therein by screwing down the ring or nut 23.

Seamer timing mechanism.—As stated, the seamer J is first moved radially inward to turn the seam, and is then moved outward to release it, while at the same time or instantly thereafter the seamer J' is moved in to set and finish the seam, after which it is moved outward to release the can and permit it to be fed away. The means for accomplishing these movements of the seamers (commonly called the timing mechanism) will now be described.

On the stationary spindle C is keyed fast (see Fig. 4) a gear P (shown in plan in Fig. 2); this serves as a sun gear around which revolve two planet gears Q Q fastened on vertical shafts R R carried by the head E (see Fig. 4). These shafts R have suitable upper and lower bearings in the members of the head, and between these bearings are formed with worms S; each worm meshes with two worm wheels T T between which it is located; two of these worm wheels are fastened on a shaft U, and the other two on a shaft U'. The shaft U carries a pair of timing cams V V for the primary seamer J; the shaft U' carries a pair of timing cams V' V' for the secondary seamer J'. The two pairs of cams are arranged symmetrically, and the two cams of each pair are alike. The cams act on rollers 24 carried by floating levers m m which are mounted to turn on pins n n having sockets in ears 25 formed on the respective slides G G. Beneath each lever is a spring 26, shown in dotted lines in Fig. 1, which presses its roller 24 up into engagement with the cam face of the cam V or V'. Each lever m has on the under side of its hub a toothed sector p constituting a partial pinion, all this being best shown in Fig. 1. These pinions p mesh with racks q which are fastened in recesses in the face of the lower plate or disk f of the head. Thus as either cam V or V' presses down the roller 24 of either lever m, the pinion teeth p of such lever execute a rolling movement in engagement with the teeth of the rack q, whereby the lever axis (on the pin n) crawls or "floats" toward the center of rotation of the head; since the pin n is held in the ears 25 of the slide G, this moves the slide G radially toward the center, carrying with it the carrier H, spindle I, and seamer J or J'. Thus the seamers are moved toward the

mandrel D as the rollers are encountered by the salient portions of the cams V V', and as the rollers drop into the hollows of these cams the springs 26, pressing up the rollers, cause a reverse movement of the floating levers m and consequently an outward sliding movement of the slides G G and their appurtenant parts. The movements are determined by the peripheral conformations of the cams V V', which are shaped as shown in Fig. 1, so as to accomplish the required succession of inward and outward movements of the respective seamers. These movements being well understood in the art, it is unnecessary to make a precise showing of the cam conformations or to precisely describe the successive movements of the seamers. It will be observed that the levers m m, being connected by their pins n, and arranged in pairs under the respective pairs of cams, have precisely like movements and thereby impart precisely parallel thrusts in radial directions to the slides G G. Thus the movements are as nearly frictionless as possible, and by reason of the rolling action of the pinions p (which act as the short arms of the levers) the action of the levers is substantially uniform throughout their angular stroke. The result is a very smooth and powerful movement for the advancing of the seamers to their work (this being done by the thrust of the cams), followed by a free retractile movement under the impulse of the springs 26. It will be observed that the cams V V' have a slow rotation (determined by the pitch of the worm S and the diameters of the worm wheels T T) in proportion to the rotation of the head, so that each seamer, after advancing to its work, will remain in active contact with the can head long enough to accomplish the seaming. The pins n are reduced at their ends, and these reduced portions overhang slide plates 27 fixed on the plate F of the head (see Fig. 9), which slide plates engage the margins 28 of the slides G. These reduced and overhanging end portions of the pins serve as stops to prevent rotary movement of the pins n as the levers m turn.

The seamers are backed against springs, so that they may yield while rolling down the seam and avoid crushing or injuring the metal. These springs W W are shown in Figs. 1, 4 and 9. They act to press down the cam shafts U U' and allow these shafts to yield upwardly in case excessive pressure is transmitted from the cam C through either seamer, its slide G and levers m to the corresponding cam tending to lift it. The springs W, instead of pressing directly down upon the shafts of the bearings U U', are shown as arranged to bear down upon the free ends of levers r r, each of which is pivoted on a pin r' hung in a bearing frame 30 which is fastened down to the plate f

of the head E. Each spring W is coiled around a pin or rod s the lower end of which is anchored in the frame 30 on a cross pin 31; the spring reacts upwardly against nuts 32 screwed on the upper end of the pin D and pressed downwardly upon the free end of the lever r.

Some details of construction remain to be described. The head E turns on the stationary spindle C, being formed with an internal bushing 40 to make a good bearing contact; at top and bottom, roller bearings 41 and 42 are provided. The shafts R R are shown as having ball bearings 43 beneath, and plain bearings above. The spindles I I are shown in Figs. 1 and 9 as projecting upwardly, and their free ends laterally guided by coming between parallel guide strips 45, 45 which act to resist any 10 tilting tendency due to the thrust of the seamers while in action. Another construction is shown in Fig. 10, where the spindle I is carried in a tubular support i' which is heavier than the support i in Fig. 6 and 15 extends somewhat higher, so as to afford an efficient lateral brace for the spindle. In this construction the clamping ring 23 is carried down to a lower level, this clamping effect on the member k' being the same as in the 20 case of the member k in Fig. 6.

Within the mandrel D is a knock-out u mounted on a stem u' which is coupled to a knock-out rod v (Fig. 6), which rod extends up through the spindle C and out at 25 the top, as shown in Fig. 4. The stem u' has any suitable interlocking engagement with the knock-out rod v to facilitate changing the knock-out u when the mandrel is changed. In such case the rod v is lowered 30 to bring the stem u' below the mandrel, and after the new mandrel is inserted a corresponding knock-out is applied, its stem being engaged with the knock-out rod and the latter elevated to bring the knock-out into 35 the recess in the mandrel. Between the knock-out rod and the bore of the spindle C is a sleeve w, being a tube movable within the spindle C, and its lower end having a threaded engagement with a neck portion on 40 the mandrel, as shown in Fig. 4. The mandrel is screwed onto this threaded portion and then the sleeve w is drawn up to bring the mandrel into place and there held by screwing on a nut w' which bears against 45 the upper end of the spindle C. A nut w² is screwed on above the nut w' and serves as a head for the sleeve w, being held from unscrewing by a screw pin 46. The sun gear K is held on the spindle C by a tapered joint, 50 the lower end of the spindle being formed as a cone 47, and the opening within the gear K is tapered to a like cone, so that as the sleeve w is drawn upward, the mandrel lifts the gear K and forces it tightly onto this 55 cone. To prevent any possible rotation of

the gear K, it is formed on its upper side with a key projection 51 which enters into a corresponding notch in a flange 52 (Fig. 1) formed on the lower end portion of the spindle C. The spindle C is held in the 60 frame A by a nut 48 screwed on its upper end. The spindle may be tapered and drawn up into a tight fit with a tapered hole in the frame A by the nut 48, or fastened securely 65 in any other suitable way. It may be keyed or splined within the frame A if desired. An alternative construction is shown in Fig. 14, where the head A is divided transversely along the axis of the spindle to form a 70 cap A' which is bolted to the main frame 75 by screws 53, the bore through which the spindle C passes being made so tight a fit with it that screwing up these screws causes the cap A' to clamp the spindle C fast. It is only essential that some secure means be 80 provided for fastening the spindle C firmly and non-rotatively to the frame.

Preferably the lower disk f of the head E is encircled by a band f² (Fig. 4) which is shown in dotted lines in Fig. 11. This band thus closes the open ends of the slide-ways f f' by forming bridges across these 85 openings. These bridge portions are shown in cross-section at f² in Fig. 6.

The bearing member l having the annular bearing 13 for the hub portion 12 of the planet gear L requires to be so mounted that it may be adjusted, or substituted by another bearing member, when changing the seamers in such manner as to require gears L 90 of different radius. For this purpose it is preferably made with parallel wing portions 55 (Fig. 5) engaged by an offset ledge 56 in supporting plates or cleats 57 clamped fast beneath the disk f by screws or bolts 95 58 (which are conveniently made the same ones which hold down the slideway plates 27). By slackening the screws 58 holding these cleats in place, the parallel marginal portions or wings 55 are released, so that the bearing plate l may be set out or in as required. To insure against its being thrown out of place by centrifugal force in case the fastening screws should accidentally slacken, plates 60 are provided which are 100 fastened beneath the cleats 57 by the same screws 58. These plates 60 have each a tooth 61 which enters a notch or groove 62 in the bearing member l, as best shown in the, broken-away portion at the left in Fig. 5. 105 For each different adjustment required for the bearing members l, a different set of plates 60 is provided. These plates occupy immovable positions, since their holes receiving the screws 58 fit closely to these screws, 110 so that the plates 60 cannot move, and consequently their teeth 61 hold the bearing members l immovably in place with respect to the sun gear. Fig. 15 shows one of the 115 plates 60 detached.

An important advantage of this machine is that the seamers, in moving toward and from the mandrel, have a straight line movement in an unvarying plane. Heretofore they have been swung from rocking centers intersecting the axes of the seamer spindles and at a point considerably above; this causes the seaming edges to move in an arc while approaching toward or receding from the mandrel. This arc movement has occasioned practical difficulty because of bringing the seaming surfaces out of the horizontal plane of the seam. To diminish this disadvantage as much as possible the points of pivotal support above have been carried up as high as was possible, which again involved another disadvantage, namely, that the revolving head was made unduly high, thus adding to the height and weight of the entire machine and requiring a longer projecting portion of the stationary central spindle, which necessitated making this undesirably large and heavy to give it proper rigidity. By mounting the seamer spindles in slides which have a horizontal rectilinear movement the seamers are caused to move in a true horizontal plane without any vertical component of motion; it results from this that the seamers approach to and recede from the mandrel in such way as to correctly engage the flanges to be seamed, and without any liability of making a distorted seam or of injuring or cutting the seam during the receding movement of the seamers.

The improved machine herein set forth is capable of operating at much higher speed than previous machines of the same general type. It in fact about doubles the output of such machines.

The operation of the mechanism herein set forth will be apparent from the foregoing description.

It will be understood that the invention is not limited to the details of construction illustrated and described, which may be varied within the scope of the appended claims and in accordance with the requirements of the machine. The illustrated machine is designed for heading filled cans which cannot be revolved without disturbing their contents; for heading empty cans, the mandrel holding the can may revolve, the operative relation of the parts in other respects being unchanged.

What I claim is:

1. A can-heading machine having a can-supporting mandrel and a seamer of complementary contour, adapted respectively to hold and seam a non-circular can, with means for positively producing a relatively rotary motion between the seamer and mandrel whereby the seamer contour is maintained in complementary relation to the non-circular contour of the can being seamed, and means for moving the seamer toward

the mandrel to seam the can and away from it to clear the can, combined with means for maintaining the seamer always in a plane at right angles to the axis of the can and with its seaming surface in the plane of the seam.

2. A can-heading machine having a can-supporting mandrel and a relatively contoured seamer, adapted respectively to hold and seam a non-circular can, with means for positively producing a relatively rotary motion between the seamer and mandrel whereby the seamer contour is maintained in complementary relation to the non-circular contour of the can being seamed, and means for moving the seamer toward the mandrel to seam the can and away from it to clear the can, combined with means for confining the seamer in such movements to a plane coincident with the plane of the seam.

3. A can-heading machine having a can support and a contoured seamer, the can support and seamer being adapted respectively to hold a non-circular can and seam the latter, means for producing a relative rotary motion between the can support and seamer whereby successive portions of the seamer are brought into contact with successive portions of the can to produce the seam, means for imparting to the seamer a positive turning movement during such relative movement, said means maintaining at all times a complementary relationship between the seamer and the can, and means for moving the seamer toward the can to seam it and away from the can to clear it, and means for maintaining the seamer always in a plane at right angles to the axis of the can.

4. A can-heading machine for stationary non-circular cans of the type having non-circular seamers of a contour reciprocal to that of the can positively rotated while revolving around the can in a circular orbit, comprising a revolving head having carriers for the seamers formed as slides movable in the revolving head in a horizontal plane, so that the seaming contours of the seamers are in a horizontal plane and move always in the plane of the seam.

5. A can-heading machine of the described type for non-circular cans, having seamers movable toward and from the mandrel and means for confining them in such movements to a horizontal plane, and gearing for rotating them relatively to the head in peripheral rolling contact with the mandrel during the seaming, said gearing adapted to rotate the seamers at like speed when retracted, so that they turn in the same relation to the mandrel whether active or idle.

6. A can-heading machine of the described type for non-circular cans, comprising a revolving head, a non-circular mandrel, a seamer of complementary contour, carried by said head and movable toward

and from the mandrel, means for confining the seamer in such movement to a horizontal plane, gears for rotating the seamer relatively to the head while in seaming engagement with the mandrel, and a coupling for continuing the rotation of the seamer at like speed when idle.

7. A can-heading machine for non-circular cans comprising a stationary mandrel 10 and sun gear, a revolving head, a non-circular seamer carried by said head, timing means for moving the seamer toward the mandrel to seam the can and away therefrom to free the can, a planet gear in constant mesh with said sun gear, a seamer gear united to the seamer and movable into and out of mesh with such sun gear, and a coupling between the planet gear and seamer gear for rotating the seamer in step with the 20 planet gear when its seamer gear is out of mesh with the sun gear.

8. A can-heading machine for non-circular cans comprising a stationary mandrel and sun gear, a revolving head, non-circular 25 seamers carried by said head, with means for moving them toward and from the mandrel, planet gears in constant mesh with said sun gear, and seamer gears united to the seamers and movable into and out of mesh 30 with such sun gear, and couplings between the respective planet gears and seamer gears for rotating the latter in step with the former when out of mesh with the sun gear.

9. A can-heading machine according to 35 claim 6, the seamer having its seamer gear and planet gear closely related to engage the same sun gear.

10. A can-heading machine according to 40 claim 6, the coupling having sliding engagement with its planet gear along one diametrical axis, and a driving engagement for its seamer gear along an axis at right angles to the former.

11. A can-heading machine of the 45 described type comprising a revolving head, slowly rotating cams carried thereby, seamer carriers movable to bring the seamers into and out of action, and springs backing said cams, whereby the reaction to the seaming 50 thrust is transmitted from the seamers through the cams to said springs.

12. A can-heading machine according to 55 claim 11, each cam turning in a movable bearing portion, and a spring stressing such bearing portion and adapted to yield to the reaction transmitted from the seamer to the cam.

13. A can-heading machine of the 60 described type, its timing mechanism comprising slowly-rotating cams carried by the head, said cams being peripherally contoured, and means engaged by their peripheral contours for communicating timing movements to the seamers, and springs acting to press the seamers toward the seam.

14. A can-heading machine of the described type comprising a stationary spindle carrying a sun gear, a head revolving around said spindle, shafts carried by said head having planet gears meshing with said sun gear and having worms, transverse shafts carried by the head having worm wheels driven from said worms, and cams carried by said transverse shafts for moving the seamers out and in. 70

15. A can-heading machine according to 75 claim 14, each transverse shaft carrying two cams, the two cams on one shaft actuating one seamer, and the two cams on the other shaft actuating the other seamer. 80

16. A can-heading machine according to 85 claim 14, the transverse shafts mounted in movable bearings, and springs stressing such bearings to enable the cams to yield to reaction from the seamers.

17. A can-heading machine according to 90 claim 14 each transverse shaft carrying two like cams, means between said cams and the seamers for communicating like thrusts from each pair of cams to the corresponding seamer, and spring-pressed bearings for said shafts adapted to yield to the reaction from the seamers. 95

18. A can-heading machine of the described type, comprising a revolving head, 100 seamer carriers mounted on said head, and timing mechanism for moving the seamers, comprising slowly-rotating cams and floating levers for communicating movement from the cams to the seamer carriers.

19. A can-heading machine of the described type, comprising a revolving head having radial slideways and seamer-carrying slides movable in such slideways, with timing mechanism for the seamers including slowly-rotating cams, and floating levers fulcrumed to said slides having rollers engaged by said cams and having pinion teeth engaging racks on the head for communicating movement from the cams to said slides. 105 110

20. A can-heading machine of the described type, comprising a revolving head having a disk portion formed with radial recesses on diametrically opposite sides, and seamer-carrying slides movable radially in 115 said recesses and including each a seamer spindle bearing portion passing upwardly through such radial recess.

21. A can-heading machine of the described type, comprising a revolving head having a disk portion formed with radial recesses on diametrically opposite sides, seamer-carrying slides movable radially in said recesses and formed each in two relatively adjustable portions comprising a main slide member engaged by timing mechanism and a spindle bearing member adjustable radially in the main slide member and having clamping portions above and below the latter, and means for forcing such portions 120 125 130

together to clamp the spindle-bearing member to the main slide member.

22. A can-heading machine of the described type, comprising a stationary mandrel and sun gear, a revolving head, seamers carried by said head movable toward and from the mandrel, planet gears in constant mesh with said sun gear, seamer gears united to the seamers and movable into and out of mesh with such sun gear, and means for rotating the seamer gears in step with the planet gears when the seamers are idle, each planet gear having a concentric hub portion, and the head carrying a bearing member for such hub portion, whereby to keep the planet gears in mesh with the sun gear.

23. A can-heading machine according to claim 22, the planet gear bearing members mounted to slide in radial slideways in the revolving head, and adapted to be set therein to fixed adjustments.

24. A can-heading machine according to claim 22, the planet gear bearing members mounted to slide in radial slideways in the revolving head, and locating plates fastened to the head having shouldered engagement with said bearing portions whereby to hold them fixedly in place against radial displacement.

25. A can-heading machine of the described type, comprising a stationary spindle and revolving head turning around the spindle, with a mandrel fastened to the spindle beneath the head, having means for fastening said mandrel to the spindle, comprising a sleeve passing through the spindle engaging the mandrel at its lower end and having fastening means at its upper end for drawing it up through the spindle into tight engagement.

40

26. A can-heading machine of the described type, comprising a stationary spindle and revolving head turning around the spindle, with a mandrel fastened to the spindle beneath the head, having means for fastening said mandrel to the spindle, comprising tapered portions on the spindle and mandrel respectively, and a sleeve passing through the spindle, engaging the mandrel at its lower end and having means at its upper end for drawing it upwardly to force said tapered surfaces into tight engagement.

27. A can-heading machine of the described type, comprising a stationary spindle and revolving head turning around the spindle, with a mandrel fastened to the spindle beneath the head, having means for fastening said mandrel to the spindle, comprising a key and socket engagement between the mandrel and spindle, and a sleeve passing through the spindle engaging the mandrel at its lower end and having means at its upper end for drawing it upwardly to hold said key and socket in place.

28. A can-heading machine of the described type, comprising a stationary spindle and revolving head turning around the spindle, with a mandrel fastened to the spindle beneath the head, having means for fastening said mandrel, and a sun gear fastened to the spindle beneath the head, and means for locking said mandrel and sun gear in place, comprising a key and socket engagement between them and the spindle, and means for drawing the sun gear and mandrel up to hold the key and socket in locked engagement.

In witness whereof, I have hereunto signed my name.

CHARLES GUERITEY.
